Primary Examiner — Austin Murphy(74) *Attorney, Agent, or Firm* — Banner & Witcoff, Ltd.(57) **CLAIM**

The ornamental design for an iron, as shown and described.

DESCRIPTION

FIG. 1 is a perspective view of an iron showing a first embodiment of our new design;

FIG. 2 is a left side view thereof;

FIG. 3 is a right side view thereof;

FIG. 4 is a front view thereof;

FIG. 5 is a top plan view thereof;

FIG. 6 is a rear view thereof; and,

FIG. 7 is a bottom plan thereof.

The broken lines shown in the drawings represent portions of the iron that form no part of the claimed design.
